UNITED STATES PATENT OFFICE.

EMANUEL CORNELIUS HELLER AND ARTENAOUS JEFFERSON EMRICK, OF GERMANTOWN, OHIO, ASSIGNEES OF ONE-THIRD TO WILLARD LINCOLN HUTCHINSON, OF GERMANTOWN, OHIO.

TUBE-CUTTER.

956,805.

Specification of Letters Patent.

Patented May 3, 1910.

Application filed June 12, 1909. Serial No. 501,834.

To all whom it may concern:

Be it known that we, EMANUEL CORNELIUS HELLER and ARTENAOUS JEFFERSON EMRICK, citizens of the United States, residing at 5 Germantown, in the county of Montgomery and State of Ohio, have invented certain new and useful Improvements in Tube-Cutters, of which the following is a specification.

10 This invention relates to tube cutters, and it has particular reference to a device of this class which can be specially adapted for cutting the tubes in water tube boilers into short lengths that may be readily removed 15 at the furnace doors, when such tubes are to be removed and replaced by new ones, one object of the invention being to provide a tube cutter of this character which shall be simple in construction, easily mounted in position for operation, and thoroughly effective in use.

20 A further object of the invention is to so construct the said tool that, by dispensing with certain portions thereof, it may be conveniently and effectively utilized for the purpose of cutting the flues of an ordinary steam boiler.

25 Still further objects of the invention are to so construct the tool that it may be readily 30 dismembered and conveniently packed or stored in a comparatively small space.

35 With these and other ends in view which will readily appear as the nature of the invention is better understood, the same consists in the improved construction and novel arrangement and combination of parts which will be hereinafter fully described and particularly pointed out in the claims.

40 In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

45 In the drawings—Figure 1 is a longitudinal sectional view showing the improved tube cutter applied in position for operation with reference to one of the tubes of a water tube boiler. Fig. 2 is a longitudinal sectional view showing the adaptation of the invention with reference to one of the flues of an ordinary steam boiler. Fig. 3 is a side 55 elevation of the cutter head. Fig. 4 is an

end view of the same. Fig. 5 is a side view of one of the cutter carrying levers. Fig. 6 is a plan view of the same. Fig. 7 is a side view of the supporting member whereby the tool is held in position for operation with reference to a water tube boiler. Fig. 8 is a sectional view taken transversely through the tubular shank of the tube cutter and showing, in elevation, the ratchet mechanism whereby the device is rotated.

60 Corresponding parts in the several figures are denoted by like characters of reference.

The cutter head A of the improved device consists of a sleeve 12 having a plurality of radiating wings 13 with arcuate outer faces 14 forming arcs of a circle the diameter of which should be approximately equal to the internal diameter of the flue or tube that is to be cut in order that the cutter head may be guided for rotation within the same. The 70 sleeve 12 is internally threaded at one end as shown at 15 to enable the cutter head to be detachably connected with the tubular shank B which is correspondingly threaded as shown at 16. The cutter head is provided 75 with a plurality of radial slots 17 extending through the wings 13 and serving for the reception of the cutter carrying levers 18 which are pivotally mounted upon pins 19 extending transversely through the wings 13 80 and are provided at their free ends with terminal out-turned hooks 20 having transverse recesses 21 in which the cutters 22 are supported for rotation; the axes of said cutters being parallel to the axis of the cutter 85 head with reference to which the said cutters will thus be transversely disposed. The cutter carrying levers 18 are preferably mounted adjacent to what would be regarded as the front end of the cutter head, and 90 they are forced inwardly within the latter by the action of suitably arranged springs 23, thus throwing the cutters normally within the perimeter of the cutter head, the side walls of the slots of which are provided 95 with notches 24 to accommodate the cutters.

100 The tubular shank B, with the front end of which the cutter head is detachably connected as hereinbefore stated, is composed of two or more sections 25, 25', which are 105 connected in axial alinement at their meeting ends by means of a sleeve or collar 26 internally engaging the tube sections which latter are rigidly connected with the sleeve or collar 26 by suitable fastening means such 110

as set screws 27, 27'. This construction enables the tubular shank to be readily disassembled when occasion shall require as will be hereinafter set forth.

5 For the purpose of actuating the cutter carrying levers to force the free ends of said levers in an outward direction against the tension of the springs 23, there is provided a conical expanding member 28 the base of 10 which is of a diameter approximately equal to the internal diameter of the bore of the cutter head within which the said expanding member is movable. Extending from the apex of the conical expanding member is a 15 terminally screw-threaded shank 29 which is detachably connected by means of a nut 30 with the forward end of the expanding rod C which extends axially through the tubular shank B, said expanding rod being intermediate supported and guided by the tubular 20 connecting sleeve 26 through which it extends. The expanding rod C is composed of two or more sections 31, 31' which are screw-threaded adjacent to their meeting ends as 25 shown at 32, 32' and separably connected by a nut 33. The rear end of the rear section 31' of the expanding rod extends through a tubular plug or guide 34 which is shrunk or otherwise firmly secured in the rear end of 30 the rear section 25' of the tubular shank, the rear extremity of said section 31' being screw-threaded as shown at 35 for the reception of an operating nut 36 bearing against the plug or guide 34 and provided with handles 37 35 whereby it may be conveniently rotated for the purpose of imparting longitudinal movement to the rod C and to the expanding member carried thereby. It is to be understood, of course, that the expander rod sections are not in threaded connection with 40 the sleeve 26 and plug 34.

Securely mounted upon the tubular shank B, adjacent to the rear end of the latter is a sleeve or collar 38 having a ratchet flange 39; 45 said sleeve or collar being mounted securely but detachably upon the shank B by fastening means such as a set screw 40. The sleeve or collar 38 affords a bearing for a lever 41 having a pivotally supported spring actuated pawl 42 that engages the ratchet flange 39 by means of which the collar 38, the shank B and the cutter head A may be rotated. An annular guide member 43 serves 50 to retain the lever or handle 41 in position upon the collar 38, with which said guide member is connected by a set screw 44.

A tubular supporting member D is provided whereby the tool or implement may be effectively supported in operative position 60 with reference to a water tube boiler, the header plates of which have been indicated at E, F in Fig. 1 of the drawings. The tubular supporting member D which affords a bearing for the tubular shank B is confined 65 between collars G, G that are secured de-

tachably upon the shank B by means of set screws 54 and said tubular supporting member is provided with an inclined flange 45 having an annular offset or shoulder 46 engaging the aperture 47 which is formed in the outer header plate F in registry with a tube a portion of which appears at 48 in Fig. 1 of the drawings. The supporting member D takes the place of the cap which is ordinarily used to close the aperture 47, 75 and the said supporting member is secured in position by means of hooked bolts 49 the shanks of which extend through the flange 45.

The operation of the invention with reference to a water tube boiler will be readily understood from the foregoing description taken in connection with Fig. 1 of the drawings, by reference to which it will be seen that the tool or implement is supported for 80 rotation by the supporting member D in axial alinement with the tube that is to be cut. It will be quite evident that by making the tubular shank B and the expanding rod C sufficiently long, the cutter head may 85 be located at any desired point within the tube, thus enabling the latter to be cut into short lengths or sections which may be readily movable at the furnace doors.

The operation of the tool will be obvious 90 to those skilled in the art to which the invention appertains; by manipulating the nut 36 the conical expanding member will 95 actuate the cutter carrying levers, forcing the cutters into engagement with the inner 100 walls of the tube which will then be cut by rotating the cutter head and the tubular shank by means of the pawl and ratchet mechanism provided for this purpose.

When the implement is to be utilized for 105 other purposes than for cutting tubes of water tube boilers, such as for the purpose of cutting the flues of an ordinary steam boiler, the nut 36 is detached from the rear section 31' of the expanding rod, and said 110 rear section as well as the connecting nut 33 are detached from the forward section 31 of the expanding rod. The rear section 25' of the tubular shank B is detached from the connecting sleeve 26 by loosening the set screw 27' and the nut 36 is then adjusted upon the screw-threaded rear end 32 of the forward section 31 of the expanding rod which, 115 it will be understood, extends through and some distance in the rear of the connecting sleeve 26 which latter will now constitute a bearing for the nut 36 to operate against. The collar 38 carrying the pawl and ratchet mechanism is mounted upon the rear end of 120 the forward section 31 of the tubular shank prior to adjustment of the nut 36, and the tool will then be found complete for operation upon the flues of an ordinary steam boiler one of which has been shown at 125 130 Fig. 2 of the drawings.

From the foregoing description taken in connection with the drawings hereto annexed, the operation and advantages of this invention will be readily understood. The 5 construction is simple, and the facility with which the improved implement may be adapted and utilized for various purposes will be appreciated by those familiar with the use of this class of devices.

10 Having thus described the invention, what is claimed is:

1. In a tube cutter, a cutter head, a plurality of cutters carried thereby, an expanding member movable longitudinally through the cutter-head, a tubular shank connected detachably with the expanding member and composed of a plurality of sections connected in axial alinement, means for guiding the expanding rod through the tubular 15 shank, a nut engaging the expanding rod and bearing against the guide means, means for rotating the tubular shank and the cutter head, and a supporting member for the tubular shank comprising a collar having an obliquely disposed shouldered flange, and hook 20 bolts extending through the latter; and means for supporting the tubular shank for 25

rotation and against longitudinal movement with reference to the supporting member.

2. In a tube-cutter, a cutter-head, a plurality of cutters carried thereby, an expanding member movable longitudinally through the cutter-head, a tubular shank detachably connected with the expanding member and composed of a plurality of sections 30 connected in axial alinement, means for guiding the expanding member through the tubular shank, a nut engaging the expanding means, means for rotating the tubular shank 40 and the cutter-head, a supporting member for the tubular shank having an obliquely disposed shouldered flange, hook bolts extending through the flange, and means for supporting the tubular shank for rotation 45 and against longitudinal movement with reference to the supporting member.

In testimony whereof we affix our signatures in presence of two witnesses.

EMANUEL CORNELIUS HELLER,
ARTENAOUS JEFFERSON EMRICK.
